KNOCK-OUT BOTTOM

Filed Aug. 29, 1928

INVENTOR.
William Salisbury

BY
Thomas J. Donnelly
ATTORNEY.

UNITED STATES PATENT OFFICE

WILLIAM SALISBURY, OF TOLEDO, OHIO

KNOCK-OUT BOTTOM

Application filed August 29, 1928. Serial No. 302,742.

My invention relates to a new and useful improvement in a knockout bottom used particularly in the pottery industry for removing the formed pots, or other receptacles or retainers, from the female die after the spinner has performed its function and has raised from operating position relatively to the worked material. In knockout bottoms as commonly used the bottom which contacts 10 with the pot, or article to be formed, is usually held non-rotating.

It is an object of the present invention to provide a knockout bottom which may be rotatable relatively to the support therefor. 15 It is another object of the invention to provide a knockout bottom which will permit the forming in the bottom of the pot, or receptacle, perforations spaced outwardly radially from the center of the pot, or receptacle, and 20 still permit the formation of the pot, or receptacle, on the automatic machines used for this purpose.

It is another object of the invention to provide a knockout bottom having a plurality of 25 perforating members projected therethrough and normally retained in position for penetrating the pot or article to be formed.

It is another object of the invention to provide a knockout bottom which will be simple 30 in structure, economical of manufacture and highly efficient in use.

Other objects will appear hereinafter.

The invention consists in the combination and arrangement of parts hereinafter described and claimed.

The invention will be best understood by a reference to the accompanying drawings which form a part of this specification, and in which,

Fig. 1 is a side elevational view of the invention showing it applied.

Fig. 2 is a top plan view of the invention.

Fig. 3 is a sectional view taken on line 3—3 of Fig. 2, and

Fig. 4 is a view taken on line 4—4 of Fig. 3.

In the drawings I have illustrated a table 7 on which is supported the female die 8, in which a spinner (not shown) is adapted to engage for spinning and forming the plastic material to conform to the shape of the female

die 8, and of the proper thickness. After the spinning operation it is desired that the formed article in the female die 8 may be removed therefrom. Supported on the inwardly projecting flange 9 of the die 8 is a flange 10 projecting outwardly from the retainer 11, to serve as supporting means for the retainer when the die is in pot forming position. This retainer member is threaded onto the knob 12, in which is threaded the actuating rod 13. The bottom 14 is provided with the centrally extending shaft 15, which is fixedly mounted thereto and which extends through the bushing 16, positioned in the retaining member 11. A bolt 17 is threaded into the lower end of the shaft 15 and engages a washer 18 which engages the end of the bushing 16. A plurality of slidable pins 19 are projected through the bottom 14, each of these pins being provided with a head 20 which engages the disc 21, having the boss 22 which engages in a peripheral groove formed axially in the bushing 16. Secured to the end of the retainer 11 and projecting upwardly therefrom in spaced relation are leaf springs 23 which engage the under surface of the disc 21 and serve to retain the pins 19 thrust outwardly beyond the outer surface of the bottom 14. The bottom 14, together with the shaft 15, is rotatable relatively to the retainer 11, thus carrying the pins 19 rotatably, so that a pot placed in the die 8 and through the bottom of which the pins 19 may project, will, if and when rotated by the spinner, carry with it the rotatable bottom 14, so that the perforations formed in the bottom of the pot will be the size of the pins 19 and no deformation effected. The springs 23 give the necessary yieldability to the bottom 14, and it will be noted that the bottom of the screw 17 is spaced from the end of the member 13 so that the shaft 15 may be, if required, moved axially relatively to the retainer 11 against the tension of the springs 23.

With a knockout bottom formed in this manner the formation of articles, or containers, such as pots and the like, with a plurality of openings in the base, may be fabricated on the automatic machines now customarily used

and an economical construction of such articles effected.

While I have illustrated and described the preferred form of my invention, I do not wish to limit myself to the precise details of structure shown, but desire to avail myself of such variations and modifications as come within the scope of the appended claims.

Having thus described my invention, what I claim as new and desire to secure by Letters Patent is:

1. A knockout bottom of the class described, comprising a retaining member, and a knockout bottom rotatably mounted on said retaining member and axially moveable with respect thereto.
2. A knockout bottom of the class described, comprising a retaining member, a knockout bottom rotatably mounted on said retaining member and axially moveable with respect thereto within predetermined limits, and a plurality of perforating members projecting outwardly from one face of said bottom.
3. A knockout bottom of the class described, comprising a retaining member, a knockout bottom rotatably mounted on said retaining member and axially movable with respect thereto within predetermined limits, a plurality of perforating members projecting outwardly from one face of said bottom, and yieldable means for normally resisting axial movement of said bottom in one direction.
4. In a knockout bottom of the class described, a retaining member, supporting means therefor, a rotatable bottom supported by said retaining member, pins projected through said bottom and extending normally above the upper face thereof, and resilient means carried by said retainer for maintaining said pins in operative position on said bottom.
5. In a knockout bottom of the class described, a retaining member, supporting means therefor, a rotatable bottom supported by said retaining member, pins projected through said bottom and extending normally above the upper face thereof, said pins being free for axial movement, an engagement member for engaging the lower ends of said pins, and resilient means carried by said retainer and engaging said engagement member for maintaining said pins in normal position.
6. A pottery forming die, a rotatable bottom, a support for said bottom, said bottom being axially shiftable as to said support.
7. A pottery forming die, a rotatable bottom, a support for said bottom and spring means between said bottom and said support.
8. A pottery forming die comprising a rotatable bottom having a depending shank, a retainer forming a bearing in which said

shank is rotatable and axially shiftable, and resilient means between said bottom and retainer.

9. A pottery forming die comprising a rotatable bottom having a depending shank, a support therefor providing a bearing for said shank, perforating members projecting upwardly from said bottom and extending through said bottom, a plate engaging said pins between said bottom and support, and spring means between the plate and support.

In testimony whereof, I have signed the foregoing specification.

WILLIAM SALISBURY.
